BABY'S BARBER CHAIR SEAT

Orman M. Rainwater, Los Angeles, Calif.

Application January 3, 1955, Serial No. 33,804

Term of patent 14 years

(Cl. D15—1)

FIG. 1

FIG.4.

Fig. 1 is a top plan view of a baby's barber chair seat embodying my new design,

Fig. 2 is an end elevation view as seen from the left of Fig. 1,

Fig. 3 is a front elevation as seen from the right of Fig. 2, and

Fig. 4 is a perspective view thereof.

I claim:

The ornamental design for a baby's barber chair seat, substantially as shown.
